GAS TURBINE PLANT

John Constantine Grey, Isleworth, England, assignor to Power Jets (Research & Development) Limited, London, England, a British company

Application June 28, 1951, Serial No. 234,116

Claims priority, application Great Britain July 3, 1950

4 Claims. (Cl. 230—9)

This invention relates to the application of gas turbine plant to the generation for extraneous use, e. g. for blowing a blast furnace, of a supply of combustion-supporting air at a pressure substantially higher than atmospheric and is more especially concerned with the control of such plant.

Plant of the kind with which the invention is concerned comprises a main turbine-driven compressor which provides the extraneous air supply and also feeds a combustion chamber from which the driving turbine receives hot gas; a separate compressor (the "gas compressor") driven by the same turbine feeds fuel gas to the combustion chamber. The control of such plant is complicated when it is necessary for the extraneous air supply to be substantially constant in pressure but variable in amount; mere throttling of the extraneous supply will result in a larger proportion of the delivery of the main compressor being diverted to the combustion chamber, with consequent variation of turbine speed (and thus delivery pressure) while an attempt to vary turbine inlet temperature (and thus to control turbine speed) by throttling the gas supply to the gas compressor will result in an intolerable pressure differential between the deliveries to the combustion chamber from the gas and main compressors respectively.

The present invention provides gas turbine plant operating on gaseous fuel and designed for the generation for extraneous use of combustion supporting air at a pressure substantially higher than atmospheric comprising a main turbine-driven compressor which provides the extraneous air supply and also feeds a combustion chamber from which the driving turbine receives hot gas, a separate turbine-driven compressor for supplying fuel gas to the combustion chamber, characterized in that turbine speed is controlled by diverting fuel gas delivered by the gas compressor before such gas reaches the combustion chamber.

Preferably, the diverting of fuel gas is effected automatically responsive to a variable delivery condition of the main compressor.

This invention may best be understood by reference to the diagrammatic drawing which shows a bypass valve so positioned as to control the amount of fuel to a combustion chamber in accordance with the output pressure of the main turbine-driven compressor. Thus, the main turbine-driven compressor is automatically controlled to accommodate changing load conditions.

An example of plant in accordance with the invention is illustrated by the accompanying diagrammatic drawing and comprises a turbine 10 driving a two-stage, centrifugal gas compressor 11 and a two-stage centrifugal air compressor 12, of which the first stage is provided with a double-sided impeller; an intercooler 13 is provided between the two stages of the main compressor 12. The delivery from the main compressor 12 is split, part being ducted to the receiving apparatus for example a blast furnace (27) by way of a duct 14 and cock 15

2

and the remainder being passed to a combustion chamber 16 from which the turbine is fed; the gas compressor 11 delivers to the combustion chamber by way of a by-pass valve 17. Dual ports 5 in valve member 18 permit the passage of gas to the combustion chamber 16.

The position of the valve member 18 of the by-pass valve is controlled by an hydraulic relay 19, the supply to which of liquid from a pump 20 is controlled by a pilot valve 21. As is well known in the art, said pilot valve 21 is obviously adapted to control the flow of the spent fluid to a reservoir (not shown) to which pump 20 is connected in a closed system. The piston of the relay and that of the valve 21 are linked to one end and an intermediate point respectively of a restoring lever 22, the other end of which is linked to an aneroid capsule 23. The capsule is mounted in a housing 24, the interior of which is subject, by way of a pipe 25, to the pressure obtaining in the delivery duct 14.

With the arrangement illustrated, increase, beyond a predetermined value, of pressure within the duct 14 results in the valve member 18 taking up a new position such that a proportion, or a greater proportion as the case may be, of the delivery of the gas compressor 11 is by-passed, being permitted to return, by way of a duct 26, to the reservoir (not shown) from which the gas compressor is fed; the reduction of the fuel supply involves reduction of the turbine inlet temperature and thus of turbine speed, with resultant reduction (i. e. restoration) of delivery pressure.

The control system just described may, of course, be applied to plant differing in detail (for example, one comprising an axial air compressor from which combustion air is bled at an intermediate stage) and offers advantages by way of fuel economy as well as of convenience.

What I claim is:

1. Gas turbine plant comprising an air compressor, a fuel gas compressor, a turbine, shaft means drivingly connecting the turbine to the said air and fuel gas compressors, a combustion chamber, first duct means conveying compressed air from the said air compressor to provide a supply of compressed air for use extraneously of the plant, second duct means conveying compressed air from the air compressor to the combustion chamber, third duct means conveying fuel gas from the gas compressor to the combustion chamber, fourth duct means conveying combustion gases from the combustion chamber to the turbine, a diverting duct positioned in the said third duct means enabling fuel gas to be diverted from the said third duct means instead of passing to the combustion chamber, valve means controlling the flow of fuel gas from the third duct means into the said diverting duct, actuating means for the valve means, a first operative connection between the actuating means and the valve means, a control device, a second operative connection between the control device and the actuating means and a connection between the control device and the said first duct means enabling the control device to be operated in response to variation of a condition of the compressed air delivered by the air compressor.

2. Gas turbine plant comprising an air compressor, a fuel gas compressor, turbine, shaft means drivingly connecting the turbine to the said air and fuel gas compressors, a combustion chamber, first duct means conveying compressed air from the said air compressor to provide a supply of compressed air for use extraneously of the plant, second duct means conveying compressed air from the air compressor to the combustion chamber, third duct means conveying fuel gas from the gas compressor to the combustion chamber, fourth duct means conveying combustion gases from the combustion chamber to the turbine, a diverting duct positioned in the said third duct means enabling fuel gas to be diverted

from the said third duct means instead of passing to the combustion chamber, valve means controlling the flow of fuel gas from the third duct means into the said diverting duct, actuating means for the valve means, a first operative connection between the actuating means and the valve means, a pressure-sensitive control device, a second operative connection between the control device and the actuating means and a connection between the control device and the said first duct means enabling the control device to be operated in response to variation from a given datum of the pressure of the compressed air delivered by the air compressor.

3. Gas turbine plant comprising an air compressor, a fuel gas compressor, a turbine, shaft means drivingly connecting the turbine to the said air and fuel gas compressors, a combustion chamber, first duct means conveying compressed air from the said air compressor to provide a supply of compressed air for use extraneously of the plant, second duct means conveying compressed air from the air compressor to the combustion chamber, third duct means conveying fuel gas from the gas compressor to the combustion chamber, fourth duct means conveying combustion gases from the combustion chamber to the turbine, a diverting duct positioned in the said third duct means enabling fuel gas to be diverted from the said third duct means instead of passing to the combustion chamber, valve means controlling the flow of fuel gas from the third duct means into the said diverting duct, a hydraulic relay, a first operative connection between the hydraulic relay and the valve means, an aneroid capsule, a second operative connection between the aneroid capsule and the hydraulic relay and a connecting pipe between the aneroid capsule and the said first duct means enabling the aneroid capsule to be operated in response to variation from a given datum of the pressure of the compressed air delivered by the air compressor.

4. Blast furnace blowing apparatus incorporating gas turbine plant comprising an air compressor, a fuel gas

compressor, a turbine shaft means drivingly connecting the turbine to the said air and fuel gas compressors, a combustion chamber, first duct means adapted to convey compressed air from the said air compressor to a blast furnace, second duct means conveying compressed air from the air compressor to the combustion chamber, third duct means conveying fuel gas from the gas compressor to the combustion chamber, fourth duct means conveying combustion gases from the combustion chamber to the turbine, a diverting duct positioned in the said third duct means enabling fuel gas to be diverted from the said third duct means instead of passing to the combustion chamber, valve means controlling the flow of fuel gas from the third duct means into the said diverting duct, actuating means for the valve means, a first operative connection between the actuating means and the valve means, a control device, a second operative connection between the control device and the actuating means and a connection between the control device and the said first duct means enabling the control device to be operated in response to variation of a condition of the compressed air delivered by the air compressor.
